METHODS AND APPARATUS FOR EXPLORING BOREHOLES

Henri-Georges Doll, Ridgefield, Conn., assignor, by mesne assignments, to Schlumberger Well Surveying Corporation, Houston, Tex., a corporation of Texas

Application April 21, 1955, Serial No. 502,777

7 Claims. (Cl. 324—2)

This invention relates to methods and apparatus for exploring boreholes and, more particularly, pertains to new and improved methods and apparatus for detecting water channels in the oil column of producing wells.

One procedure employed heretofore to locate intruding water involves the introduction of a conditioning fluid to the well and usually a hydrostatic pressure is established to provide a substantially static column in the well. This conditioning fluid may, for example, have an electrical conductivity different from that of the intruding water and thus diffusion of the intruding water into the conditioning fluid may be measured electrically.

The foregoing method has not always been entirely satisfactory since production of the well must be interrupted for an undesirably long period. This is due to the fact that often the establishment of the required static pressure condition is very time consuming and in many instances the procedure for establishing the pressure condition must be repeated a number of times before a satisfactory result can be obtained.

It is an object of the present invention, therefore, to provide new and improved methods and apparatus for detecting water intrusion in a well that are not subject to the above-described deficiencies of prior arrangements.

Another object of the present invention is to provide new and improved methods and apparatus for detecting water intrusion in a producing well requiring substantially no interruption in production.

A method of determining fluid intrusion in a flowing well in accordance with the invention comprises the steps of passing a pair of closely spaced electrodes into the well without substantially interrupting the flow of fluids from the well, and obtaining indications of the electrical impedance between the electrodes while fluid continues to flow from the well.

To carry out the foregoing method, it is within the contemplation of the present invention to provide apparatus for detecting fluid intrusion in a well. This apparatus comprises a pair of electrodes supported in spaced relationship relative to the longitudinal axis of the well. Means are provided for displacing the electrodes about an annular path in a plane transverse to the aforesaid axis of the well, and the apparatus further comprises means for deriving indications of an electrical characteristic of material between the electrodes.

The novel features of the present invention are set forth with particularity in the appended claims. The present invention, both as to its organization and manner of operation, together with further objects and advantages thereof, may best be understood by reference to the following description taken in connection with the accompanying drawings in which:

Fig. 1 is a view, partly in longitudinal cross section, of a lubricator device by means of which apparatus embodying the present invention may be introduced into a flowing well;

Fig. 2 is a view in longitudinal cross section of appara-

2

tus for detecting fluid intrusion in a well constructed in accordance with the invention;

Fig. 3 represents a modification which may be made to a portion of the apparatus shown in Fig. 2; and

Fig. 4 is a view in longitudinal cross section of another modification which may be made to the apparatus of Fig. 2.

In Fig. 1, a housing 10 carrying apparatus embodying the present invention is shown in association with typical well head equipment 11 at the surface of a well. Equipment 11 includes a riser 12 connected at its upper end to a sleeve 13 wherein a suitable pressure seal may be provided in a conventional manner. Where the well pressure is too high for conventional seals, the sleeve 13 may enclose a pressure lubricator 14 as shown, which may be of the type described in the copending application of M. P. Lebourg, filed May 19, 1954, bearing the Serial No. 430,868 and assigned to the same assignee as the present invention.

The pressure lubricator 14 includes gland sections 15 and 16 removably secured within sleeve 13 by a cap 17 and having interfaces defining a bore 18 adapted to receive a cable 19 which supports housing 10 for movement through the well so that it may be lowered and raised through tubing 20 that traverses the well. Fluid channels 21 and 22 provide fluid communication between a section 23 in the lower portion of bore 18 and a source 24 of sealing liquid via suitable pipe connections. The sealing liquid is under a pressure slightly higher than well pressure and excess sealing liquid is passed via a port 25 in the upper end of gland section 16 to a reservoir 26.

In order to insert housing 10 into the well, the well head valve is closed and cap 17 removed so that the gland sections 15 and 16 of lubricator 14 may be removed. Housing 10 is then lowered into riser 12 and the lubricator is reassembled. The well head valve may then be opened and pressure applied to lubricator 14 so that as cable 19 is passed through the lubricator, a pressure seal is maintained and undue wear on the cable is precluded. Thus, the well may be returned to production after a very short, insignificant interruption and the apparatus embodying the invention may be lowered through tubing 20 and into well casing 27 where it may be used to determine fluid intrusion. For example, water intrusion may occur via a crack in casing 27 and may flow in continuous, vertical channels.

In Fig. 2, housing 10 is shown in operative position within casing 27, through which fluid 28 flows in an upward direction. The housing is provided with upper and lower sets 29 and 30 of three or four bowed springs. These springs are biased outwardly relative to housing 10 so that after the apparatus leaves tubing 20 and enters casing 27, they move into engagement with the casing and thus serve to center the housing in the casing.

If desired, an alternative arrangement of retractable, motor driven arms may be employed to center the housing in the casing, such as disclosed in the copending application of D. F. Saurenman and M. P. Lebourg, filed March 30, 1954, Serial Number 419,678, and assigned to the same assignee as the present invention.

A shaft 31 rotatably supported within housing 10 projects through a suitably sealed opening 32 in the lower end of the housing. One pair of electrode wires 33 and 34 extend radially from shaft 31 in diametrically opposite directions. They are mechanically connected to the shaft by coiled springs 35 and 36 but electrically insulated therefrom, and are constructed of a resilient material, such as steel. The length of each electrode wire is greater than the radius of the casing 27 and to preclude electrical contact with the casing, end members 37 and 38 of electrically insulating material are fixed to the ends

of the wires 33 and 34, another pair of similar electrode wires 39 and 40, connected to shaft 31 by springs 41 and 42, is positioned a short distance, on the order of one inch, for example, below electrode wires 33 and 34. These electrode wires are provided with end insulators 43 and 44. The electrodes 33 and 34 are electrically connected to one another by a conductive collar 45 on shaft 31, and the electrodes 39 and 40 are connected by a similar collar 46.

Electrodes 33, 34 and 39, 40 are connected by leads 47 and 48 that extend through shaft 31 to slip rings 49 and 50 mounted to, but electrically insulated from an upper end portion of shaft 31 within housing 10. A pair of brushes 51 and 52 complete sliding electrical connections between the slip rings 49 and 50 and a pair of conductors 53 and 54. Conductors 53 and 54 are connected to the secondary winding of a one to twenty step-up transformer 55 having its primary winding connected to insulated leads 56, 57. These leads extend through cable 19 and are connected to a source 58 of electrical energy at the earth's surface. Source 58 may supply an alternating potential at 110 volts and is provided with an operating switch 59.

In series with the secondary of transformer 55 is the primary winding of a twenty to one step-down transformer 60. The secondary winding of transformer 60 is connected by insulated leads 61 and 62 which extend through cable 19 to an indicator 63. The indicator 63 may, for example be a recording voltmeter in which the recording medium is displaced in proportion to movement of housing 10 through the well.

In order to rotate electrodes 33, 34 and 39, 40 about an annular path in a plane transverse to the axis of the well, a driving motor 64, is mounted within housing 10 and is mechanically coupled to the upper end of shaft 31 by an appropriate gear system 65. The motor is electrically connected to conductors 56 and 57 and thus is coupled to source 58.

If desired, housing 10 may be filled with a suitable electrically insulating fluid 66 and a bellows 67 may be mounted to the periphery of an opening 68 in the side wall of the housing. Thus, the fluid pressure within the housing may be automatically regulated to compensate for the usual increase in pressure of fluid 28 experienced by the housing as it descends, and leakage of well fluids into the housing is minimized.

A typical embodiment of the invention may be adapted to be inserted into tubing on the order of 2 inches in diameter. The diameter of housing 10, the retracted diameter of bowed springs 29 and 30 and the retracted condition of electrodes 33, 34 and 39, 40 are arranged so that the instrument may move freely in the tubing, as shown in Fig. 1. In the casing the springs 29 and 30 expand to engage the casing, and the electrodes 33, 34 and 39, 40 become extended as shown in Fig. 2. Thus, switch 59 may be closed to energize transformer 55 and motor 64. Housing 10 may then be lowered or drawn upwardly through casing 27 with the electrodes 33, 34 and 39, 40 rotating about the axis of the housing. Since the housing is centered by bowed springs 29 and 30, the rotation of the electrodes occurs about an annular path in plane transverse to the axis of the well.

Since a relatively high voltage, on the order of a few thousand volts, is impressed across the electrodes, when they intercept an essentially vertical water channel, the resistance between them drops from a value of several megohms to a few hundred ohms, and an electrical break down occurs across the electrodes. This immediately causes a high voltage to appear at the primary of transformer 60 and an indication is obtained.

A record of such indications is obtained in device 63 as a function of depth of housing 10 in the well, and thus the level at which water enters may be determined.

Inasmuch as source 58 provides an alternating potential, motor 46 may be of the synchronous type so

that its speed is fixed and the electrodes 33, 34 and 39, 40 rotate at a known speed. Accordingly, by using an indicator that is sufficiently fast in its response, and knowing the vertical spacing between the electrodes and the resistivity of the intruding water, some indication of the size of the intruding water column 27 may be obtained.

It is therefore evident that the present invention provides an effective method for determining water intrusion in a well. Moreover, apparatus embodying the present invention may be used in a flowing well without interrupting flow for any of more than an extremely short interval of time. Hence, the present invention is not subject to the deficiencies of prior arrangements.

If desired, the electrode wires may take the alternative form illustrated in Fig. 3. Intermediate coil spring 70 and insulator 71, wire 72 is provided with a plurality of sharply-pointed, thin lateral extensions 73. Since surface tension draws any oil film toward the wire, upon encountering water, the likelihood of an oil film remaining on the extremities of the extensions is reduced. Thus, breakdown between electrode wires may be more readily obtained.

Another electrode arrangement, shown in Fig. 4, comprises thin, blade-like sets of electrode 75, 76 and 77, 78. These electrodes are connected to a hollow shaft 79 by respective pivots 80, 81, 82 and 83 for movement about respective horizontal axes. They extend through elongated, opposed openings 84 and 85 in shaft 79 and are biased about their axes by spiral springs 86, 87, 88 and 89 to bring insulated tips 90, 91, 92 and 93 into engagement with the inner wall of casing 94.

Pivotedly connected to adjacent end portions of electrodes 75 and 77 is a rod 95 of electrically insulating material which serves as a shaft for a roller 96 of electrically insulating material. Similarly, a roller 97 is supported by a shaft 98 pivotally connected to adjacent end portions of electrodes 76 and 78. Thus, when shaft 79 is rotated, the electrodes are driven about annular paths with the rollers 96 and 98 riding on the inner wall of casing 94.

A retracting sleeve 99 is slidably supported by shaft 79 and is provided with opposed openings 100 and 101 through which the electrodes project. To retract the electrodes, sleeve 99 is driven downwardly and upper portions 102 and 103 of the peripheries of openings 100 and 101 engage electrodes 75 and 76. Since these electrodes are connected to electrodes 77 and 78 by rods 95 and 98, all the electrodes are thus pivoted against the bias of springs 86-99 toward the axis of shaft 79. Conversely, to condition the apparatus for operation, sleeve 99 is driven upwardly and the electrodes 75-78 are thereby permitted to be extended.

While particular embodiments of the present invention has been shown and described, it is apparent that changes and modifications may be made without departing from this invention on its broader aspects, and therefore the aim in the appended claims is to cover all such changes and modifications as fall within the true spirit and scope of this invention.

I claim:

1. A method of detecting fluid intrusion in a flowing well which comprises the steps of: passing a pair of closely spaced electrodes into the well without substantially interrupting the flow of fluids from the well; continuously displacing said electrodes effectively to examine substantially all the material in a plane transverse to the axis of the well; and obtaining indications of an electrical characteristic of material between the electrodes while fluid continues to flow from the well.

2. A method of detecting fluid intrusion in a flowing well which comprises the steps of: passing a pair of closely spaced electrodes into the well without substantially interrupting the flow of fluids from the well; rotating said electrodes at a predetermined speed about an annular path laterally displaced from and enclosing the

axis of the well and disposed in a plane transverse to the axis of the well; and obtaining indications of an electrical characteristic of material between the electrodes while fluid continues to flow from the well.

3. Apparatus for detecting fluid intrusion in a well comprising: a pair of electrodes, adapted to traverse a well; means for supporting said electrodes in spaced relationship relative to the longitudinal axis of the well for rotation about an annular path in a plane transverse to the aforesaid axis; means for displacing said electrodes about said path; and means for deriving indications of an electrical characteristic of material between said electrodes.

4. Apparatus for detecting fluid intrusion in a well comprising: a pair of long, narrow conductive wires adapted to traverse a well extending radially a distance on the order of magnitude of one-half the diameter of the well in spaced parallel relationship to one another relative to the longitudinal axis of the well, said wires being supported for rotation about an annular path in a plane transverse to the aforesaid axis; means for displacing said wires about said path; and means for deriving indications of an electrical characteristic of material between said wires.

5. Apparatus for detecting fluid intrusion in a well comprising: a housing adapted to traverse a well; a pair of electrodes supported by said housing in spaced relationship relative to the longitudinal axis of the well for rotation about an annular path in a plane transverse to the aforesaid axis; means connected to said housing for maintaining a portion thereof and said electrodes in fixed relation to the aforesaid axis as said housing is passed through the well; means for displacing said electrodes about said path; and means for deriving indications of an electrical characteristic of material between said electrodes.

6. Apparatus for detecting fluid intrusion in a well comprising: a carrier adapted to traverse a well; a pair of electrodes supported by said carrier in spaced relationship relative to the longitudinal axis of the well for 40

rotation about an annular path in a plane transverse to the aforesaid axis; means connected to said carrier for maintaining a portion thereof and said electrodes in substantially fixed relation to the aforesaid axis as said carrier is passed through the well; means for displacing said electrodes about said path; means for impressing a relatively high voltage between said electrodes to effect an electrical discharge therebetween upon encountering material in the well of a predetermined electrical conductivity; and means for deriving indications responsive to such an electrical discharge.

7. Apparatus for detecting fluid intrusion in a well comprising: a carrier adapted to traverse a well; a shaft supported by said carrier for rotation about a given axis; 15 a pair of electrodes supported by said shaft, electrically insulated from one another, and extending away from said shaft in essentially parallel relation to one another; means connected to said carrier for maintaining a portion thereof in substantially fixed relation to the longitudinal axis of the well with said given axis essentially aligned with the aforesaid longitudinal axis as said carrier is passed through the well; means for rotating said shaft thereby to displace said electrodes about an annular path; and means for deriving indications of an electrical characteristic of material between said electrodes.
